(57) CLAIM

The ornamental design for a note dispenser, as shown and described.

DESCRIPTION

FIG. 1 is a perspective view of a note dispenser showing our new design;

FIG. 2 is a top view thereof;

FIG. 3 is a bottom view thereof;

FIG. 4 is a front view thereof, a rear view being a mirror image thereof;

FIG. 5 is a left side view thereof, a right side view being a mirror image thereof; and,

FIG. 6 is a perspective view thereof in condition of use.

The broken lines showing a note in FIG. 6 are environment and form no part of the claimed design. All other broken lines illustrate portions of the note dispenser that form no part of the claimed design.
